[57] CLAIM

The ornamental design for a convex display panel, as shown
and described.

DESCRIPTION

FIG. 1 is a perspective view of a convex display panel
showing our new design;

FIG. 2 is a top plan view thereof, the bottom plan view being
a mirror image;

FIG. 3 is a front elevational view thereof;

FIG. 4 is a rear elevational view thereof; and,

FIG. 5 is a side elevational view thereof, the other side being
a mirror image.
